ADVANCING REEL THREADING DEVICE

Arthur E. Guenther and Lee B. Molyneux, Buffalo, N. Y., assignors to E. I. du Pont de Nemours & Company, Wilmington, Del., a corporation of Delaware

Application May 10, 1946, Serial No. 668,848

19 Claims. (Cl. 28—71.5)

1

This invention relates to a threading device, and more particularly to a device for threading yarn on a yarn-advancing reel enclosed in a casing.

Recently, there has been devised yarn-advancing reels of the general type wherein a yarn is wound in a substantially helical form around a reel having a set of fixed yarn-carrying bars arranged concentrically around and rotatable in a fixed circular path about the center axis of the reel axle and a set of movable bars which during rotation about the center axis of the reel axle move radially (vary their distance from the center axis of the reel axle) and axially, the axial movement of the movable bars being such that when the bars are in the yarn-contacting position (radial out position), such bars will be moved in the direction of the yarn advancement across the reel to advance the yarn across the reel and, when the movable yarn bars are out of contact with the yarn, such bars will be moved axially in the direction opposite to the direction of the yarn advancement across the reel.

It has been found that when freshly regenerated cellulose yarn was wound on a yarn-advancing reel of the aforementioned type and the reel enclosed in a steamer, highly effective carbon bisulfide removal could be obtained. However, considerable difficulty was encountered in the threading of the yarn on the reel. The yarn had to be manually threaded before steam was introduced into the steamer, with the result that there was a considerable amount of yarn which was not subjected to the steaming operation. Various means were attempted to mechanically thread the yarn on the advancing reel in the steamer, but none of these were successful.

An object of this invention is to provide a new and novel device for threading yarn on a yarn-advancing reel enclosed in a casing.

Another object of this invention is to provide a threading device for a yarn-advancing reel enclosed in a steamer wherein the yarn on the reel is subjected to a steam treatment.

An additional object of this invention is to provide a threading device which prevents the escape of steam from the casing of the steamer enclosing the yarn-advancing reel.

A further object of this invention is to provide a threading device having a head provided with flexible seals which will deflect locally to permit introduction of a threading key therebetween and will adjust themselves to the contour of such key to prevent the escape of steam from the casing of the steamer enclosing the reel.

2

A still further object of this invention is to provide a threader having a feeder which positions the hook on the leading end of a threading key in the path of the rotating reel so that it will be engaged by one of the bars on the reel and pulled out of the threading device.

A still further object of this invention is to provide a threading key which, during passage through the feeder, will firmly grip the yarn at the trailing end thereof.

A still further object of this invention is to provide means to release the threading key from the reel after the yarn has been wound in a substantially helical form on the reel to the desired point of discharge of the yarn from the reel.

Other and additional objects will become apparent hereinafter.

The objects of the invention are accomplished, in general, by providing a threading device having a feeder, projecting through an opening in the casing and so disposed that the lower end thereof is positioned on the inside of a steamer casing adjacent the path of the rotating reel, and a head on the upper end of the feeder which is disposed outside of the casing.

The feeder is provided with means so that, when a threading key having a hook on the leading end thereof is passed therethrough, the hook will be disposed at the lower end of the feeder in the path of travel of the rotating reel and in position to be engaged by one of the bars of the reel enclosed in the casing and be pulled out of the feeder upon rotation of the reel.

The head of the threading device is provided with a slot through which the threading key is inserted into the feeder. Means are provided to completely close off a passage through the slots. The passage closing means, which are flexible, will deflect locally to permit passage of the threading key between them and will adjust themselves to the contour of such key to prevent escape of steam from the steamer enclosed in the reel.

Means are provided on the head to position the yarn in the path of travel of the trailing end of the threading key so that, as the latter passes in and through the feeder, the yarn will be firmly gripped in a wedge-shaped slot at the trailing end of the threading key.

The back of the threading key is maintained in contact with the bar which engages it by the tension of the yarn which is gripped at the trailing end of the threading key.

As the reel rotates, the advancing end of the

threading key is hooked over one of the movable bars and is carried with it, first being carried toward the discharge end of the reel and then being returned toward the loading end of the reel so that at the completion of one revolution of the reel the hook would still be in alignment with its starting position unless it is shifted out of that position by some other means. Thus, about the middle of the first revolution of the reel, the head of the hook engages a stationary cam mounted from the roof of the steamer and this cam shifts the threading key one pitch toward the discharge end of the reel. As the reel revolves, a helix of yarn is wound onto the reel. This rope is under some tension and, as it is advanced along the reel, it pushes the threading hook along ahead of it, in successive wraps as long as the hook remains engaged with the reel bar or until the hook has been fed over the end of such bar. Means are preferably provided to release the threading key from the reel bar at the point where it is desired to have the yarn leave the reel, as by pushing its hook off the end of the bar which engages it. The releasing means, in a specific form, comprises a cam located to engage the hook at a position where it is travelling downwardly so that, as the hook is removed from the bar, it will fall and carry the end of the yarn with it to the bottom of the reel casing. The yarn, due to its own weight, will continue to fall to the bottom of the casing as it unwinds from the revolving reel.

Preferably, the yarn is fed from the spinning machine and positioned on the head so that it can be threaded onto the reel. In one embodiment, the yarn is fed from the spinning machine beneath a guide hook carried on the head of the feeder and around a post also carried on the head of the feeder, and thence to a waste roll. The threading key is inserted and positioned in the feeder so that the wedge-shaped slot at the trailing end of the threading key will grip the yarn as it passes from the hook to the post and carry it downwardly through the feeder and onto the reel. The post is provided with a cutter and, as the trailing end of the threading key descends, the yarn will be carried over a cutting wheel in the post, with the result that the yarn which had been running from the post of the waste roll will be reversed in direction and run over the knife, whereby it will be cut in two. The cut occurs between the threading key and the waste roll and leaves the yarn end coming from the spinning machine wedged in the trailing end of the threading hook and, in consequence, follows it on through the threading device and onto the reel.

The drag caused by drawing the yarn between the sealing means in the head of the threading device also imposes a tension which aids in maintaining the key on the reel.

The present invention will be more clearly understood by reference to the following detailed description when taken in connection with the accompanying drawings, in which:

Figure 1 is an elevation of the feeder in position on the steamer casing in which a yarn-advancing reel is enclosed, a portion of the casing being shown in section and the reel being shown diagrammatically;

Figure 2 is a plan view of the feeder head;

Figure 3 is an enlarged elevation of the feeder in position on the casing;

Figure 4 is a section taken on the line 4-4 of Figure 2;

Figure 5 is a section taken on the line 5-5 of Figure 2;

Figure 6 is an elevation of a plug used in connection with the passage sealing means;

5 Figure 7 is a view of the end at the right of the feeder shown in Figure 3;

Figure 8 is a bottom view of the feeder;

Figure 9 is a section taken on the line 9-9 of Figure 7;

10 Figure 10 is a section taken on the line 10-10 of Figure 7;

Figure 11 is a section taken on the line 11-11 of Figure 7;

Figure 12 is a partial section showing the insertion of the threading key at the beginning of the threading operation;

Figure 13 is a partial section illustrating another stage in the threading operation; and

20 Figure 14 is a section taken on the line 14-14 of Figure 13.

Referring now to the drawings wherein like reference numerals designate like parts, the reference numeral 10 designates a casing of a steamer. Since any form of steamer can be used and the 25 details of construction of the steamer form no part of this invention, no further description thereof is necessary.

A yarn-advancing reel, which is shown diagrammatically in Figure 1 of the drawings, is 30 enclosed by the casing 10 and in one form comprises movable channel-shaped bars 14 and fixed bars 16. The fixed bars 16 are arranged concentrically around and rotated in a fixed circular path about the center axis of the reel axle, and

35 the movable bars 14 are mounted and positioned so that, during rotation thereof about the center axis of the reel, they will move radially (vary their distance from the center axis of the reel) and axially (oscillate longitudinally relative to the fixed bars). The movable bars 14 are so mounted that, when they are in yarn-contacting position, they will be moved axially of the reel in the direction of the yarn advancement and, when they are out of yarn-contacting position,

40 such bars will be moved axially of the reel in the direction opposite to the direction of yarn advancement across the reel. In operation of such reel, the yarn, from a suitable source of supply, is wound in a substantially helical form around 45 the reel, and, upon rotation of the reel, the yarn will be progressively fed across the reel to the point of discharge. Since the precise details of construction of the yarn-advancing reel form no essential part of the invention, no further description thereof is deemed necessary.

The casing 10 is provided with an opening 20 which is opposite to the yarn-receiving end of the reel and is provided with a frame 22. A plate 24 is secured to the frame 22 by means of bolts 26. 50 A gasket 28 is positioned intermediate the plate 24 and the frame 22 to make the joint steam-tight.

The plate 24 is provided with an opening which is in alignment with the opening 20 of the casing 10. A feeder, generally designated by the reference character F, extends through such aligned opening and is secured to the plate 24, as will hereafter be more fully explained.

As shown in Figures 1 and 3, the feeder F is 70 angularly disposed relative to the casing 10 and terminates interiorly of the casing with the lower end thereof positioned adjacent the path of travel of the bars 14 and 16 of the yarn-advancing reel.

The upper end of the feeder F which terminates 75 outside of the casing 10 includes a head, gener-

ally designated by the reference character H. The head H is formed of a block 38, in the top of which the bottom end of a hook 32 is secured. A post 36, in spaced relationship to the hook 32, is threadedly secured on the top of the block 38, as shown in Figure 4. The post 36 is provided with a slot in which a circular knife 40 is carried on a pin 50. The circular knife 40 extends in a notch 52 in the post 36.

Intermediate the hook 32 and the post 36, the block is provided with a slot 56 which extends from the top to the bottom of the head and through which a threading member is inserted. In order to prevent escape of steam or gas from the casing 10 through the slot 56, there is provided a pair of round tubes 60 and 62 which extend longitudinally of the slot and contact at the center of the slot 56 to completely close off a passage through the slot. Since the threading key must be passed between the tubes 60 and 62, the latter are preferably made of a flexible material, such as rubber, neoprene, etc., which will deflect locally to permit passage of the threading key and the yarn therebetween and adjust themselves to the contour of the object passing therebetween.

In each of the tubes 60 and 62, there is positioned a plug, generally designated by the reference numeral 66 (see Figure 6). The plug 66, as shown in Figures 4 and 5, is provided with cylindrical ends 68 formed integrally with a semi-cylindrical piece 70. The plugs 66 are substantially equal in length to the tubes 60 and 62, and the diameter of the ends 68 thereof is approximately the same as that of the inner diameter of the tubes. The curvature of the member 70 is approximately on a radius equal to the radius of the tubes.

A plug 66 is positioned in the tube 60 so that the flat surface of the semi-cylindrical member 70 is as shown in Figure 4. At each end, a flat-headed screw 72 secures both the tube 60 and the plug 66 to a block 74 which is slidably positioned in a channel 76 between the top and bottom of the block 38. As shown in Figure 5, each screw 72 extends through a hole in the tube 60 and is threadedly secured in tapped holes 69 in the cylindrical ends of the plug 66.

A plug 66 is also positioned in the tube 62, as shown in Figures 4 and 5. The plug in tube 62 is appropriately secured to the tube at the cylindrical ends 68 thereof, which are in turn appropriately secured to the head.

As shown in Figure 4, the flat surfaces of the semi-cylindrical members 70 of the plugs 66 are positioned in the tubes in opposed relationship so that the contacting portions of the tubes opposite thereto will be free to flex when an object is inserted therebetween.

The block 74, as previously mentioned, is slidably positioned in the channel 75 between the top and bottom of the head. Movement of the block 74, and hence the tube 60, relative to tube 62, is obtained by rotation of the knurled headed members 76. As shown in Figure 5, the inner end of each stem 80 of each member 76 is secured to the block 74. The stem is also provided with a threaded portion which cooperates with a threaded hole in the flanged side plate 84, which is appropriately secured to the block 38 of the head. Thus by rotation of the knurled headed members 76, tube 60, together with its plug, can be adjusted relative to tube 62.

A knurled headed screw 86, the stem of which extends through the side plate 84, constitutes a

stop which cooperates with the block 74. As shown in Figure 4, the stem of the screw 86 is threaded and cooperates with a tapped hole in the plate 84. A lock washer 87, cooperating with a threaded boss 88 on the side plate 84, serves to lock the knurled headed screw 86 in adjusted position. To adjust the tube 60 relative to the tube 62, the screw 86 is rotated in the proper direction to release the block 74. The screws 76 are then rotated in proper direction to move the block 74 together with the tube 60 in the desired direction. Upon adjustment, the screw 86 is rotated until the end of the stem engages the block 74.

15 A front plate 100 is secured to the block 38 by screws 84. A rear plate 96 is also similarly secured to block 38. For reasons which will become apparent, the right side of the head is inclined as indicated by the reference numeral 98.

20 A plate 102 is appropriately secured, as by welding, to the bottom of the head H. At one side of plate 102, the top end of a downwardly extending plate 110 is secured, as by welding. The plate 112 is formed with a flange 104 at the bottom thereof which is secured, as by welding, to supporting plate 24. The inclined surface 98 of the head H is secured, as by welding, to the plate 24, as shown in Figures 1 and 3.

25 A front plate 108 is secured at the top thereof, as by welding, to plate 100. A short, downwardly extending, back plate 110 is secured, as by welding, in spaced parallel relationship to plate 108. The lower end of plate 110 is secured, as by welding, to an outwardly extending flange 112 of a downwardly extending plate 114 which is in spaced parallel relationship with plate 108. For reasons which will become apparent, the bottom edge of a downwardly extending plate 116 is secured to the flange 112 and one of the side edges secured to the plate 110 so that, as shown in Figures 8 to 11 inclusive, the plate 116 is positioned at right angles to plate 110 and extends inwardly therefrom.

30 As shown in Figure 7, a groove 120 is provided throughout the length of the feeder. At the top of the feeder, as shown in Figure 11, the groove 120 is formed between plate 116 and a plate 122. The plate 122 is secured to the plate 108 and is positioned at right angles to plate 108, and, as shown in Figures 8 to 11 inclusive, extends inwardly and downwardly of the feeder. Plate 122 is also disposed in parallel spaced relationship to plate 102. A plate 124 is secured at one side adjacent the inner edge of plate 122 and, at its other edge, is secured to plate 102. A guide plate 126, constituting the closed side of groove 120, is positioned intermediate the plate 124 and the plate 114, and is secured thereto by bolts 128. A downwardly extending plate 130, parallel to plate 122, is secured at one side thereof to plate 108. The plate 130 terminates at its inner side in spaced relationship to plate 114 to form a channel 131 which has a slot 121 in alignment with the groove 120.

35 The feeder above the flange 112 is of greater cross-section than that below the flange and, due to the manner of securing it onto the casing, no steam or gas can pass from the steamer through the feeder to the surrounding atmosphere. In order for any steam to pass from the steamer to the atmosphere, it must pass through the head, which is provided, as hereinbefore explained, with seals (rubber tubes 60 and 62).

40 The feeder is mounted on the casing at an angle so that the lower end is positioned ad-

jacent the path of travel of the yarn-advancing reel. In order to position such lower end in close proximity to the path of travel of the yarn-advancing reel, the plate members of the feeder are curved on a radius from the center of the reel. Specifically, plates 108 and 114 are each curved adjacent the bottom thereof on a radius from the center of the reel. Plate 130 terminates at the bottom thereof adjacent the top of the curved portion of plate 108.

The threading key (see Figures 1, 12, 13, 14) comprises a circular rod 140 of a length which extends between two successive channel bars 14 of the reel. At the bottom, the circular rod 140 has secured thereto a hook 142. The hooked member is formed of flat metal and is substantially of the form and shape shown in Figures 1 and 13. The inner surface 143 of the toe 144 is of a shape to conform to the bar of the reel which it is to engage. In the form shown, since the hook 142 is to engage a movable bar having a flat side, the inner surface 143 of the toe 144 is also flat so that it will be in close intimate contact with the side of the movable bar it engages. The edge 146 of the hook 142 which spans the channel is flat. The toe 144 is of such length that it will not be kicked off the bar which it engages during the radial outward movement of the movable bar 14. The outer edge of the hook 142 is curved, as indicated by the reference numerals 146 and 148, and also rounded. The hook 142 is of such dimensions that, as hereafter explained, when the rear edge thereof rides in groove 120, the toe will extend and project from slot 121.

The top of the circular rod 140 is bent downwardly to form a wedge-shaped slot 152 and then bent, in the form shown in Figure 12, to form an eye 154, which constitutes a handle. It is to be noted that the hook 142 and the wedge slot 152 together with the eye 154 are positioned in planes which are approximately 90° to each other.

The eye 154 is slightly inclined to the vertical axis of the rod 140, and the hook 142 is secured to the lower end of the rod so that, when the hook 142 is in engagement with a fixed bar, the eye 154 will span the following fixed bar and the rod will extend between said bars and lie on the periphery of the reel.

In operation, a yarn 160 is drawn from the spinning machine by a positively driven roller 162, from which it is passed beneath the guide hook 32, thence around the post 36, from which it passes to an appropriately mounted waste roller 164 where it is temporarily wound. To thread the yarn onto the reel, the operator, facing the device same as an observer of Figure 1 and holding the hook approximately parallel with the feeder and with the hook end down and the hook toe extending away from him, thrusts the hook through the slot 56 and past the rubber tubes 60 and 62 at a point immediately beyond the pass of the yarn from the hook 32 to the post 36, and designated as Y in Figure 12. As shown in Figure 13, the tubes yield locally to permit insertion of the hook and rod and immediately conform to the shape of the article therebetween. On leaving the head, the hook passes into the chamber designated as 170 (see Figure 11) of the enlarged portion of the feeder. During this operation, the hook slides on plate 116. When the lower end of the hook has descended to near the bottom of the enlarged portion of the feeder, as to the line designated as N—N in Figure 12, the threading key is rotated 90° on its longitudinal axis (see

Figures 13 and 14). Due to plate 130, the heel of the hook is shifted so that it enters the groove 120. As the hook continues its descent, the toe thereof enters and travels in the slot 121 and the eye 154 will travel in the channel 131. It is to be noted that the toe projects from the slot 121. The groove 120 is of such shape that, when the hook 142 is disposed in the lower curved end of the feeder, the hook, and particularly the toe, will be in the path of the bars on the rotating yarn-advancing reel. The necessary shape of the groove is obtained by appropriately curving the edge of plates 126, and which constitutes the closed end of the groove 120.

When the hook has been depressed so that it is in the path of the bars on the rotating yarn-advancing reel, the toe thereof is engaged by one of the bars on the reel and, due to the rotation of the reel, is pulled out of the feeder. After the threading key has been rotated 90° as previously explained, the trailing end of the key projects over the yarn, passing beneath the guide hook 32 onto the post 36 (pass Y). Upon further descension of the key, the yarn is caught in the wedge-shaped slot 152 wherein it is tightly secured and is carried down, together with the key, past the rubber tubes through the feeder and onto the reel following the hook. The toe of the hook is hooked over one of the yarn bars and is held there by the tension in the yarn. This tension is due to a stretch imposed in the yarn prior to being withdrawn by the roll 162, and also some drag is caused by drawing the yarn between the two rubber-sealing tubes in the head of the threading device.

During descension of the trailing end of the threading key, the eye passes through the channel designated by the reference numeral 131. After the yarn has been gripped and upon further descension of the key in the feeder, the yarn will be pulled downwardly toward the base of the post 36 until it passes over the cutter 48 in the post 36. At this moment, the yarn, which had been running from post 36 to the waste roll 164, will now be caused to pass from the hook 32 to the feeder, and the yarn passing from the post 36 to the waste roll will reverse its direction and, in trying to run over the knife, will be severed. The severing occurs between the threading key and the waste roll and leaves the yarn end coming from the spinning unit wedged in the slot 152 of the threading key and, in consequence, follows it on through the threading device and onto the reel.

After the key has hooked over the yarn bar and about the middle of the first revolution of the reel thereafter, the head of the hook engages a stationary cam (not shown) mounted from the roof of the steamer. This cam shifts the threading key one pitch toward the discharge end of the reel. As the reel revolves, a helix of yarn is wound onto the reel. This yarn is under some tension and, as it is advanced along the reel, it pushes the threading hook along ahead of it. This will continue as long as the hook remains engaged with the reel bar or until the hook has been actually fed over the end of the bar. In the preferred form, it is desirable to have the yarn leave the reel when it gets to a predetermined distance from the end of the bar, and this is accomplished by releasing the threading key from the reel bar by pushing the hook off the end of the bar. In the form shown in Figure 1, this is accomplished by a cam 166 located so as to engage the hook at a position where it is

traveling downwardly, so that, upon disengagement from the bar, the hook will fall and carry with it the end of the yarn to the bottom of the reel casing. The yarn, due to its own weight, will continue to fall to the bottom of the casing as it unwinds from the rotating reel.

The cam 166 is positioned in the path of travel of the hook on the bar of the rotating reel at the point where it is desired to have the yarn leave the reel. The cam 166 is secured, as by screws 180, to a support appropriately mounted on the interior of the casing.

During the threading operation, the yarn coming from the spinning machine continues to pass under the hook guide 32 and then down into the slot 56 between the rubber tubes 60 and 62 and downwardly through the threading device. After the reel has been threaded, the operator pulls the yarn towards him so that it is removed from under the hook 32 whereby the yarn will pass directly from the draw roll 162.

The draw roll 162 and feeder are positioned so that when the yarn passes therefrom directly to the feeder and thence onto the reel it will do so on a line tangent to the reel surface and to the tubes at a point on the line of contact therebetween.

The threading device of this invention is not restricted to any specific type of advancing reel. In general, it can be utilized with any advancing reel and wherein the yarn is advanced progressively across the reel in substantially helical form by axial movement in the direction of the yarn advancement of movable bars when in yarn-contacting position. Such reel may or may not have fixed yarn-contacting bars. Application Serial No. 633,399, filed December 7, 1945, Serial No. 640,231, filed January 10, 1946, Serial No. 644,939, filed February 1, 1946, Serial No. 644,940, filed February 1, 1946, Serial No. 645,718, filed February 6, 1946, application of Arthur E. Guenther for Yarn-advancing reel, filed May 23, 1946, and application of Robert A. Stafford for Yarn-advancing reel, filed March 23, 1946, disclose several types of reels which can be threaded by the present invention.

Though it is preferred that the hook guide 32 and the post 38 be mounted on the head of the feeder, it is not essential. Any appropriate means for positioning the yarn in position for threading can be used. Likewise, any severing means properly positioned can be used for severing the yarn passing to the waste roll after the reel has been threaded.

The use of the threading device is not restricted to threading a yarn-advancing reel enclosed in a steamer. It can be used to thread a yarn-advancing reel enclosed in any casing wherein the yarn is subjected to treatment with a fluid.

The invention is particularly applicable for threading yarn composed of continuous filaments or staple fibers, ropes, ribbons and other similar articles of continuous length onto a yarn-advancing reel enclosed in a casing wherein, while the article is being advanced across the reel, it is being subjected to a treatment with a fluid, either liquid or gaseous.

The invention provides a relatively inexpensive threading device for quickly and effectively threading continuous length articles onto a yarn-advancing reel enclosed in a casing. Due to the manner in which the feeder is positioned on the casing and the flexible seals, substantially no gas

will pass from the interior of the casing to the atmosphere through the feeder.

Since it is obvious that many changes and modifications can be made in the above-described details without departing from the nature and spirit of the invention, it is to be understood that the invention is not to be limited thereto except as set forth in the appended claims.

We claim:

1. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end thereof is passed, a pair of flexible tubes disposed in said slot and contacting at the center thereof to completely seal off a passage through said slot, said tubes being sufficiently flexible to yield and conform to the contour of the threading key and yarn when passing therebetween, and means in said feeder to guide the threading key as it descends so that the hook thereof will be disposed in the path of travel of the bars of said reel and in position to be engaged by said bars when it is in the lower end of said feeder.

2. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end thereof is passed, a pair of flexible tubes disposed in said slot and contacting at the center thereof to completely seal off a passage through said slot, said tubes being sufficiently flexible to yield and conform to the contour of the threading key and yarn when passing therebetween, means in said feeder to guide the threading key as it descends so that the hook thereof will be disposed in the path of travel of the bars of said reel and in position to be engaged by said bars when it is in the lower end of said feeder, and means positioned in the path of travel of said hook on said reel to remove said key from said reel at a predetermined place.

3. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end thereof is passed, a pair of flexible tubes disposed in said slot and contacting at the center thereof to completely seal off a passage through said slot, said tubes being sufficiently flexible to yield and

conform to the contour of the threading key and yarn when passing therebetween, and means in said feeder to guide the threading key as it descends so that the hook thereof will be disposed in the path of travel of the bars of said reel and in position to be engaged by said bars when it is in the lower end of said feeder, said tubes being disposed so that a line tangent to the periphery of said reel will pass through the line of contact of said tubes.

4. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end thereof is passed, means to feed a yarn across said slot in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, and means in said feeder to guide the threading key as it descends so that the hook thereof will be disposed in the path of travel of the bars of said reel and in position to be engaged by said bars when it is in the lower end of said feeder.

5. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end is passed, a feed roll to feed the yarn to be threaded on the reel, a waste roll receiving said yarn prior to the threading thereof on said reel, means in the path of travel of the yarn between said feed roll and waste roll to direct said yarn across said slot in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, and means in said feeder to guide the threading key as it descends so that the hook thereof will be disposed in the path of travel of the bars of said reel and in position to be engaged by said bars when it is in the lower end of said feeder.

6. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent

cent the path of travel of said rotating yarn-advancing reel, said feeder having a head positioned outside the casing and provided with a slot through which a threading key having a hook on the leading end and yarn-gripping means at the trailing end is passed, a feed roll to feed the yarn to be threaded on the reel, a waste roll receiving said yarn prior to the threading thereof on said reel, means in the path of travel of the yarn between said feed roll and waste roll to direct said yarn across said slot in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, means in said feeder to guide the threading key as it descends so that the hook thereof will be disposed in the path of travel of the bars of said reel and in position to be engaged by said bars when it is in the lower end of said feeder, and means to sever the yarn in the pass from the feed roll to the waste roll whereby the yarn can be fed directly from said feed roll through the feeder and onto said reel.

7. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end is passed, a feed roll to feed the yarn to be threaded on the reel, a waste roll receiving said yarn prior to the threading thereof on said reel, means in the path of travel of the yarn between said feed roll and waste roll to direct said yarn across said slot in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, means in said feeder to guide the threading key as it descends so that the hook thereof will be disposed in the path of travel of the bars of said reel and in position to be engaged by said bars when it is in the lower end of said feeder, and means to sever the yarn in the pass from the feed roll to the waste roll whereby the yarn can be fed directly from said feed roll through the feeder and onto said reel, said feed roll and tubes being positioned so that the yarn will pass directly from said feed roll to the slot on a line tangent to the reel surface and the line of contact between said tubes.

8. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-

advancing reel, said feeder having a head positioned outside the casing and provided with a slot through which a threading key having a hook on the leading end and yarn-gripping means at the trailing end thereof is passed, a feed roll to feed the yarn to be threaded on the reel, a waste roll receiving said yarn prior to the threading thereof on said reel, a hook guide and a post positioned on opposite sides of said slot and in the path of travel of said yarn from said feed roll to said waste roll whereby in its passage to said waste roll the yarn will first pass beneath said hook guide and then around said post and the yarn passing from said hook guide to said post will be in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, and means in said feeder to guide the threading key as it descends so that the hook thereof will be disposed in the path of travel of the bars of said reel and in position to be engaged by said bars when it is in the lower end of said feeder.

9. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening and having its lower end terminating adjacent the path of travel of said rotating yarn-advancing reel, said feeder having a head positioned outside the casing and provided with a slot through which a threading key having a hook on the leading end and yarn-gripping means at the trailing end is passed, a feed roll to feed the yarn to be threaded on the reel, a waste roll receiving said yarn prior to the threading thereof on said reel, a hook guide and a post positioned on opposite sides of said slot and in the path of travel of said yarn from said feed roll to said waste roll whereby in its passage to said waste roll the yarn will first pass beneath said hook guide and then around said post and the yarn passing from said hook guide to said post will be in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, means in said feeder to guide the threading key as it descends so that the hook thereof will be disposed in the path of travel of the bars of said reel and in position to be engaged by said bars when it is in the lower end of said feeder, and means to sever the yarn passing from said hook to said post whereby the yarn can be fed directly from said feed roll through the feeder and onto said reel, said feed roll and tubes being positioned so that the yarn will pass directly from said feed roll to the slot on a line tangent to the reel surface and the line of contact between said tubes.

10. In an apparatus for threading yarn or the like onto a rotating yarn-advancing reel having yarn-contacting bars arranged around the periphery thereof and enclosed in a casing having an opening opposite the yarn-receiving end of said reel, a feeder projecting through said opening

and having its lower end terminating adjacent the path of travel of said rotating yarn-advancing reel, said feeder having a head positioned outside the casing and provided with a slot through which a threading key having a hook on the leading end and yarn-gripping means at the trailing end is passed, a feed roll to feed the yarn to be threaded on the reel, a waste roll receiving said yarn prior to the threading thereof on said reel, a hook guide and a post positioned on opposite sides of said slot and in the path of travel of said yarn from said feed roll to said waste roll whereby in its passage to said waste roll the yarn will first pass beneath said hook guide and then around said post and the yarn passing from said hook guide to said post will be in position to be engaged by the gripping means on the threading key when said key is caused to descend in said feeder, a pair of flexible tubes disposed in said slot and contacting at the center thereof to completely seal off a passage through said slot, said tubes being sufficiently flexible to yield and conform to the contour of the threading key and yarn when passing therebetween, means in said feeder to guide the threading key as it descends so that the hook thereof will be disposed in the path of travel of the bars of said reel and in position to be engaged by said bars when it is in the lower end of said feeder, and a knife on said post to sever the yarn passing from said hook to said post whereby the yarn can be fed directly from said feed roll through the feeder and onto said reel, said feed roll and tubes being positioned so that the yarn will pass directly from said feed roll to the slot on a line tangent to the reel surface and the line of contact between said tubes.

11. In an apparatus as set forth in claim 1 having means to adjust the tubes relative to each other.

12. In an apparatus as set forth in claim 1 wherein the means in the feeder to guide the threading key comprises an appropriately shaped groove in which the rear edge of said hook passes.

13. In an apparatus as set forth in claim 1 wherein the means in the feeder to guide the threading key comprises an appropriately shaped groove in which the rear edge of said hook passes and a slot in which the toe of said hook passes.

14. In an apparatus as set forth in claim 1 wherein said feeder is provided with a channel through which the yarn-gripping means on the trailing end of the threading key passes.

15. In an apparatus as set forth in claim 1 wherein the means in the feeder to guide the threading key comprises a channel through which the trailing end of said key passes, said channel having a groove in which the rear edge of the hook of said key passes and a slot in which the toe of said hook passes.

16. A key for threading yarn on a yarn-advancing reel having contacting bars arranged around the periphery thereof which comprises a rod having on the leading end thereof a hook adapted to be engaged by said bars, said rod having on its trailing end a wedge-shaped slot which is adapted to engage the yarn.

17. A key for threading yarn on a yarn-advancing reel having contacting bars arranged around the periphery thereof which comprises a rod having on the leading end thereof a hook adapted to be engaged by said bars, said rod being bent at its trailing end to provide a wedge-shaped slot which is adapted to engage the yarn.

18. A key for threading yarn on a yarn-advancing reel having contacting bars arranged

15

around the periphery thereof which comprises a rod having on the leading end thereof a hook adapted to be engaged by said bars, said rod being bent at its trailing end to provide a wedge-shaped slot which is adapted to engage the yarn, said hook and yarn-engaging means being disposed in vertical planes approximately 90° to each other.

19. A key for threading yarn on a yarn-advancing reel having contacting bars arranged around the periphery thereof which comprises a rod having on the leading end thereof a hook

5

10

16

adapted to be engaged by said bars, said rod being bent at its trailing end to provide a wedge-shaped slot which is adapted to engage the yarn, said hook and yarn-engaging means being disposed in vertical planes approximately 90° to each other, said key being of a length so that when the hook is engaged by a bar on the reel the yarn-gripping means will be disposed on the next trailing bar on the reel.
